A. WINTON.

VALVE STRUCTURE FOR INTERNAL COMBUSTION MOTORS.

APPLICATION FILED APR. 25, 1919.

1,376,060.

Patented Apr. 26, 1921.

Inventor,
Alexander Winton
By Brookfield Mfg Co
Milwaukee.

UNITED STATES PATENT OFFICE.

ALEXANDER WINTON, OF LAKEWOOD, OHIO.

VALVE STRUCTURE FOR INTERNAL-COMBUSTION MOTORS.

1,376,060.

Specification of Letters Patent. Patented Apr. 26, 1921.

Application filed April 25, 1919. Serial No. 292,687.

To all whom it may concern:

Be it known that I, ALEXANDER WINTON, a citizen of the United States, residing at Lakewood, in the county of Cuyahoga and 5 State of Ohio, have invented certain new and useful Improvements in Valve Structures for Internal-Combustion Motors, of which the following is a specification.

The invention forming the subject matter 10 of this application relates to internal combustion engines and particularly to means for preventing the overheating of the exhaust valves.

In internal combustion engines, especially 15 of the light compression type, great difficulty results from the overheating of the exhaust valves. Indeed, the heat acting upon these valves is so great that many times the head of the valve becomes de- 20 formed due to the hammering of the valve upon its seat when so heated. Heretofore there has been no very convenient manner of cooling this valve. In the present application, however, an arrangement is dis- 25 closed for circulating a cooling medium about the head of the valve, thereby lowering the temperature thereof to such an extent as to prevent deformation of the valve and injury thereto.

30 The invention may be further summarized as consisting in the construction and combination of parts hereinafter set forth in the following description, drawings and claim.

35 In the drawing, the figure represents the upper portion of a part of a cylinder with a head applied thereto, the parts being shown in section to show the invention.

In the embodiment shown, 1 represents a 40 cylinder having a head 2 applied thereto. The head 2 is provided with an exhaust opening 3 and an intake opening 4. The intake opening receives a valve cage 5 adapted to receive and guide an intake valve 45 stem 6 having a valve head 7.

In like manner this exhaust valve opening 3 receives an external valve cage comprising a valve seat portion 8, webs 9 and an upper guide 10. This guide 10 is integral with a hollow cylindrical portion 11 which extends out above this cylinder head. The upper open end of this cylindrical portion 11 is closed by a piston guide 12 slid-

ably mounted in the cylindrical portion 11. This piston guide 12 has a central valve 55 stem opening 13 for the exhaust valve stem 14 which extends down through the entire valve cage structure and is provided with a valve 15 at its lower end adapted to co-operate with the valve seat portion 8. The 60 piston guide 12 engages a pin 14' passing through the valve stem 14. A spring 15' is arranged between the piston guide and the guide 10 for holding the former against the pin 14'. 65

The cylindrical portion 11 is provided with a side threaded opening 16 receiving an air or other cooling fluid pipe 17 connected to an air pump 18 or any other source of cooling fluid supply. Suitable 70 openings 19 extend through the guide 10 in a direction to direct the discharge of cooling medium from the chamber in the cylindrical portion 11 against the valve within the seat portion 8. The exhaust 75 valve cage is located in an exhaust chamber 20 which is in communication with an exhaust port 21 so that the air directed against the exhaust valve and its seat discharges freely into this exhaust chamber 80 and out through the exhaust port.

From the foregoing it will be seen that the cool air delivered to the hollow cylindrical portion will be delivered to the valve cage and valve in a manner to keep these 85 parts cool and prevent their becoming overheated.

What I claim is:—

In an internal combustion motor, a cylinder, a head therefor having an exhaust 90 valve cage opening and an exhaust chamber in communication therewith, an exhaust valve cage mounted therein and comprising a valve seat portion and an air chamber member connected therewith, said 95 air chamber member having a valve stem opening therethrough and a series of air discharge openings surrounding said stem opening, an exhaust valve having a stem passing through said stem opening, and 100 means for supplying air to said air chamber member.

In testimony whereof I affix my signature.

ALEXANDER WINTON.
